(57) **CLAIM**

The ornamental design for a beverage container, as shown and described.

DESCRIPTION

FIG. 1 is a perspective view of a beverage container showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof, shown in a first open position; and,

FIG. 9 is a perspective view thereof, shown in a second open position in use with an environmental straw.

The portions of the beverage container shown in broken line in FIG. 7 form no part of the claimed design. The broken lines showing of an environmental straw in FIG. 9 depict environment and form no part of the claimed design.

1 Claim, 9 Drawing Sheets
